FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

RADIO MODULATION SYSTEM.

Application filed July 11, 1922. Serial No. 574,317.

To all whom it may concern:

Be it known that I, FRANK CONRAD, a citizen of the United States, and a resident of Pittsburgh, in the county of Allegheny and 5 State of Pennsylvania, have invented a new and useful Improvement in Radio Modulation Systems, of which the following is a specification.

My invention relates to radio telephone 10 transmission and it has particular relation to means for measuring the modulation and to methods of and apparatus for controlling the modulation.

One object of my invention is to provide 15 a meter registering the alternating-current component of the modulated current supplied to an oscillator tube, said meter being calibrated to indicate directly the ratio of the effective alternating-current component 20 to .7 times the steady direct-current component.

A further object of my invention is to 25 provide a mechanism and a method of operation wherein the intensity of the modulation is controlled in accordance with a chart showing various average effective 30 values of the modulating current or, in general, of the modulation envelope. Such values are worked out with respect to the 35 different kinds of sound being transmitted in such manner that the loudest individual units of the sound shall not, in general, cause the instantaneous intensity of modulation to materially exceed the value at which distortion from over-modulation begins, as more fully described hereinafter.

With these and other objects in view, my 40 invention consists in the methods of operation and in the details of apparatus herein- 45 after described and claimed, and illustrated in the accompanying drawing, wherein—

Figure 1 is a diagrammatic view of circuits and apparatus embodying a preferred 45 form of my invention, and

Figure 2 is a similar view showing a modification.

In order to make clear disclosure and to 50 illustrate the principles of my invention, I shall describe it in detail with reference to a preferred form, although it is to be under-

stood that various modifications and substitutions of equivalents known to those skilled in the art may be adopted without departing from the spirit and scope of the invention.

In Fig. 1 is shown a conventional oscillation generator and modulation system comprising an oscillator tube 3 having a plate 4, a grid 5 and a filament 6, and an oscillator tube 7 having a plate 8, a grid 9 and a filament 10. The plate circuits of both tubes are connected in parallel across a common source shown as a high-voltage battery 11, having a large choke-coil 12 in series therewith.

The grid circuit of the modulator tube is connected to suitable amplifier devices associated with a telephone circuit. The grid circuit of the oscillator tube is connected, through a grid condenser 13 and a grid leak 14, to variable taps 15 and 16 on a coil 17. The plate of the oscillator tube is also connected to said coil 17 through a stopping condenser 18. An antenna circuit, comprising an antenna 19 and a ground connection 20, is also connected to the coil 17.

The circuits so far described comprise a well known transmission system wherein the choke-coil 12 causes the source 11 to supply a substantially constant current and wherein 30 modulation of the plate-current supplied to the oscillator tube 3 is effected by means of variable currents drawn by the plate circuit of the modulator tube 7. A radio-frequency choke-coil 21 is included in the 35 connections between the oscillator plate 4 and the source for preventing loss of radio-frequency energy.

In order to indicate the amount of modulation, a so-called modulation meter has been 40 developed. As shown, a current transformer is provided having an iron core 22 constructed of very thin laminations and designed for a substantially constant ratio of primary current to secondary current over 45 a wide range of frequency values. The transformer has a primary winding 23 connected in series with the supply circuit for the oscillator plate 4 and it has a secondary winding 24 which may be connected to any 50 55 60 65 70 75 80 85 90 95 100

instrument capable of correctly indicating the current throughout the desired frequency range.

A thermo-ammeter is shown comprising 5 a heating element 25 connected across the terminals of the secondary winding 24, a thermo-couple 26 responsive to the temperature of the heating element 25 and a galvanometer 27 connected across the terminals of 10 the thermo-couple. An air gap 22a is provided in the transformer core to prevent saturation by reason of the direct-current component of the plate current.

In the operation of a radio telephone 15 transmission system, such as that described above, complete modulation occurs when the current drawn by the oscillator tube varies from zero to twice the steady current supplied by the source. However, faithfulness 20 in reproduction usually requires that the modulation intensity shall not exceed, in general, about 40 or 50 percent of complete modulation. Heretofore, it has been practically impossible to obtain the desired condition 25 at all times, both on account of the lack of convenient meters for indicating modulation intensities and on account of the fact that certain individual notes of the transmitted sound are louder than others, 30 and this discrepancy varies widely according to the nature of the sound being transmitted.

I have found that, by measuring the average effective value of the modulation current or of the modulation ratio, and by preparing 35 a chart in advance, showing suitable average effective values for the different kinds of sound to be transmitted, a current indicator, such as that hereinabove described, may be utilized to secured the best 40 modulation value in accordance with the kind of sound being transmitted and the corresponding values prescribed by said chart, as will be more fully hereinafter explained.

45 I have, therefore, calibrated my galvanometer 27 with a scale marked from zero to 100% modulation. In order to calibrate this meter, two methods are available. In the first method, the steady direct current supplied by the battery 11 is first measured. Then, the maximum permissible effective 50 value of the alternating plate current would be .7 times the steady value of the direct current. The transformer windings 23 and 55 24 are then arranged to give such transformation ratio that a full-scale deflection of the galvanometer corresponds to the maximum alternating current.

The second method of calibrating the 60 meter involves the use of an oscillograph. As sound is applied to the transmitting set, the oscillations in the detector circuits of the oscillograph are observed. When the oscillations reach 100% of the fixed component 65 of the high-frequency oscillations, the

meter should give full-scale deflection. It will be understood, of course, that the oscillograph, in this case, is either connected directly in the antenna circuit or coupled thereto. When the full-scale deflection has been determined by either of the above methods, the meter scale is then calibrated in percentage of modulation, taking 100% as the full-scale deflection, or any other system of calibration may be adopted as may be desired.

As hereinabove indicated, a chart is prepared indicating the various average values of the deflection necessary to produce the desired modulation results, in accordance with the different kinds of sound to be transmitted. Thus, in popular broadcasting service, when the announcer is speaking into the transmitter, the modulation amounts to about 40 percent, with maximum between 70 and 80 percent. Piano solos average about 30 percent, violin solos 20 to 30 percent and vocal numbers 40 to 50 percent with a maximum of 100 percent. Of course, the modulation meter indicates only the average volume of sound. While the meter may read only 30 percent, in case of piano music, the individual notes at the instant of striking may reach 80 to 90 percent. In violin solos, the music is usually quiet, but loud chords are likely to occur which would result in bad distortion if the average percentage of modulation were not kept rather low. Allowing for the kind of sound being transmitted, that is, piano, speaking voice, solo, etc., the modulation meter provides a convenient means for finding the correct distance to place the artist from the pick-up transmitter, or for adjusting the amplification of the amplifiers.

In Fig. 2 is shown a slightly modified system in which the saturating effect of the direct-current component is avoided by employing a secondary winding 23' having a mid-tap 28 which is connected to the source of supply, one portion of the secondary winding being connected in the oscillator circuit and the other portion in the modulator circuit. In this manner, the direct current normally flows in opposite directions to the respective plate circuits. The alternating components in the two plate circuits are opposite in phase and hence the alternating components are accumulative and cause a deflection of the galvanometer 27. In this case, the core 22' of the transformer does not require an air gap to prevent saturation. In other respects, the circuits and apparatus shown in Fig. 2 are the same as those shown in Fig. 1.

I claim as my invention:

1. A modulation meter comprising a current transformer, a current-measuring device associated with said transformer and means for causing said device to indicate

- the ratio of the actual modulation current to the maximum modulation current possible without undesirable distortion.
2. The combination with a conductor carrying a modulated direct current having a substantially constant unidirectional component and a variable alternating component, of a modulation meter comprising a current transformer associated with said conductor, a current-measuring device associated with said transformer and means for causing said device to indicate the ratio of the actual alternating-current component to the maximum value possible.
3. The combination with a conductor carrying a modulated direct current having a substantially constant unidirectional component and a variable alternating component, of a modulation meter comprising a current transformer associated with said conductor, a current-measuring device associated with said transformer and means for causing said device to indicate ratios of the effective values of the alternating-current component to a predetermined fraction of the constant unidirectional component.
4. The combination with a conductor carrying a modulated direct current having a substantially constant unidirectional component and a variable alternating component, of a modulation meter comprising a current transformer associated with said conductor, a current-measuring device associated with said transformer and a scale for said device calibrated in ratios of the effective values of the alternating-current component to .7 times the constant unidirectional component.
5. In a radio telephone transmitting system, the combination with a source of modulated direct current having a substantially constant unidirectional component and a variable alternating component, of an oscillation generator generating high-frequency currents modulated in accordance with said source, a current transformer associated with said source, a current-measuring device associated with said transformer and means for causing said device to indicate the ratio of the actual alternating-current component to the maximum value possible without undesirable distortion.
6. In a radio telephone transmitting system, the combination with a source of modulated direct current having a substantially constant unidirectional component and a variable alternating component, of an oscillation generator generating high-frequency currents modulated in accordance with said source, a current transformer associated with said source, a current-measuring device associated with said transformer and means for causing said device to indicate ratios of the effective values of the alternating-current component to .7 times the constant unidirectional component.
7. In a radio telephone transmitting system, the combination with a source of modulated direct current having a substantially constant unidirectional component and a variable alternating component, of an oscillation generator generating high-frequency currents modulated in accordance with said source, a current transformer associated with said source, a current-measuring device associated with said transformer and a scale for said device calibrated in ratios of the effective values of the alternating-current component to .7 times the constant unidirectional component.
8. The combination with a conductor carrying a modulated direct current having a substantially constant unidirectional component and a variable alternating component, of a modulation meter comprising an iron-core current transformer associated with said conductor, means for preventing saturation of said transformer core by reason of said unidirectional component, a current-measuring device associated with said transformer and means for causing said device to indicate the ratio of the actual alternating-current component to the maximum value possible without undesirable distortion.
9. The combination with a conductor carrying a modulated direct current having a substantially constant unidirectional component and a variable alternating component, of a modulation meter comprising an iron-core current transformer associated with said conductor, the core of said transformer having an air-gap, a current-measuring device associated with said transformer and means for causing said device to indicate the ratio of the actual alternating-current component to the maximum value possible without undesirable distortion.
10. The combination with a conductor carrying a modulated direct current having a substantially constant unidirectional component and a variable alternating component, of a modulation meter comprising an iron-core current transformer associated with said conductor, means for preventing saturation of said transformer core by reason of said unidirectional component, a current-measuring device associated with said transformer and means for causing said device to indicate ratios of the effective values of the alternating-current component to .7 times the constant unidirectional component.
11. The combination with a conductor carrying a modulated direct current having a substantially constant unidirectional component and a variable alternating component, of a modulation meter comprising an iron-core current transformer associated with said conductor, the core of said transformer having an air-gap, a current-measuring device associated with said transformer and means for causing said device to indicate ratios of the effective values of the alternating-current component to .7 times the constant unidirectional component.

- 4
- uring device associated with said transformer and a scale for said device calibrated in ratios of the effective values of the alternating-current component to .7 times the 5 constant unidirectional component.
12. In a radio telephone transmitting system, the combination with a source of modulated direct current having a substantially constant unidirectional component and a 10 variable alternating component, of an oscillation generator generating high-frequency currents modulated in accordance with said source, an iron-core current transformer associated with said source, means for preventing saturation of said transformer core by reason of said unidirectional component, a current-measuring device associated with said transformer and means for causing said device to indicate ratios of the effective 15 values of the alternating-current component to .7 times the constant unidirectional component.
13. In a radio telephone transmitting system, the combination with a source of modulated direct current having a substantially constant unidirectional component and a 20 variable alternating component, of an oscillation generator generating high-frequency currents modulated in accordance with said 25 source, an iron-core current transformer associated with said source, the core of said transformer having an air gap, a current-measuring device associated with said transformer, and means for causing said device to 30 indicate ratios of the effective values of the alternating-current component to .7 times the constant unidirectional component.
14. In a radio telephone transmitting system, the combination with a source of modulated direct current having a substantially constant unidirectional component and a 35 variable alternating component, of an oscillation generator generating high-frequency currents modulated in accordance with said 40 source, an indicating instrument responsive to the average effective value of the alternating component of said modulated direct current, means for varying the intensity of modulation, and a chart showing various values of the average alternating components desirable for different kinds of sound being transmitted, substantially as described.
15. The method of securing an effective 45 utilization of an indicating instrument responsive to the average effective value of the alternating component of a modulated direct-current supplied to an oscillation generator, in conjunction with a chart showing various values of the average alternating components desirable for different kinds of sound being transmitted, substantially as described, said method consisting in varying the intensity of modulation in such manner 50 as to cause the indications of said instrument to conform, in general, to the corresponding values prescribed by said chart.
16. In radio telephone transmission, the method of controlling the intensity of modulation of the direct current supplied to an 55 oscillation generator consisting in securing an indication responsive to the average effective value of the alternating component of the modulated direct current and varying the intensity of modulation in accordance with the information obtained from such indication.
17. In radio telephone transmission, the method of controlling the intensity of modulation of the direct current supplied to an 60 oscillation generator consisting in securing an indication responsive to the average effective value of the alternating component of the modulated direct current and varying the intensity of modulation in such manner as to cause said indications to conform substantially to predetermined average values dependent upon the kind of sound being transmitted, said predetermined average values being 65 so chosen for each kind of sound that the loudest individual notes of the sound shall not, in general, cause the instantaneous effective value of the alternating component to materially exceed .7 times the direct-current component.
18. In radio telephone transmission, the method of controlling the intensity of modulation of the direct current supplied to an oscillation generator, consisting in causing the alternating component of the modulated direct current to approximate certain predetermined average values, dependent upon the kind of sound being transmitted, said predetermined average values being so chosen for each kind of sound that the loudest individual notes of the sound shall not, in general, cause the instantaneous maximum value of the alternating component to materially exceed the direct-current component.
19. A method of radio telephone transmission comprising the step of varying the intensity of modulation in such manner that the modulation envelope approximates certain predetermined average values relative to the steady unmodulated wave and dependent upon the kind of sound being transmitted, said predetermined average values being so chosen for each kind of sound that the loudest individual notes of the sound shall not, in general, cause the momentary intensity of modulation to materially exceed the value at which distortion from over-modulation begins, substantially as described.
20. A radio telephone transmission system comprising a radio-frequency source, means for modulating the same, an indicating instrument responsive to average values of the intensity of modulation, and a chart showing certain predetermined average values relative to the steady unmodulated wave and de- 125 130

pendent upon the kind of sound being transmitted, said predetermined average values being so chosen for each kind of sound that the loudest individual notes of the sound shall not, in general, cause the momentary intensity of modulation to materially exceed the value at which distortion from over-

modulation begins, substantially as described.

In testimony whereof, I have hereunto 10
subscribed my name this 5th day of July, 1922.

FRANK CONRAD.
